UNITED STATES PATENT OFFICE

JOSEPH F. JAWOROWSKI, OF CLEVELAND, OHIO, ASSIGNOR OF FIVE-EIGHTEENTHS TO SAMUEL E. DETTELBACH, FIVE-EIGHTEENTHS TO SAM EMERSON AND TWO-EIGHTEENTHS TO EDGAR HAHN, ALL OF CLEVELAND, OHIO

ROTARY PUMP

Application filed August 18, 1930. Serial No. 475,872.

My invention pertains to rotary pumps, and is an improvement relating to the type and kind of pump shown and described in my application for patent, Serial Number 5 243,810, filed Dec. 31, 1927 now Patent No. 1,827,088, of October 13, 1931. Thus, in the present pump my general object is to simplify the interior construction of the pump and its manufacture, especially the structure involving the intake and discharge portions 10 of the pump and the movable abutments interposed and operating therebetween, all as hereinafter more specifically shown and described, and substantially as delineated in the 15 accompanying drawings, in which Fig. 1 is an end view of the pump with the face plate removed, and Fig. 2 is a sectional view vertically and longitudinally through the pump. Fig. 3 is a cross section vertically through the 20 pump on line 3—3 of Fig. 2, and Fig. 4 is a similar view on line 4—4 of Fig. 3. Fig. 5 is a plan view and horizontal section through the upper part of the pump on line 5—5 of Fig. 2, and Fig. 6 is a sectional view in perspective of the pump body. Figs. 7, 8, and 9, 25 are perspective views of the central division wall for the pump, one of the circular pistons, and one of the slidable abutment members, respectively.

The pump comprises a main body 2 having flat end faces 3—3' to which separate covers or closure plates 4—4' are removably secured by bolts 5. Bosses or extensions 6—6' on the plates 4—4' provide bearings for the driven 30 shaft 7 of the pump, and one of these bearings includes packing rings 8, a gland member 9, and an adjusting nut 10. Closure plate 4 includes a fluid passage 11 drilled at an inclination through its seating face to the closed 35 end of the shaft opening in bearing 6, whereby the fluid or liquid passing through one of the pump chambers may be utilized to lubricate the enclosed end 7' of the shaft.

A single round opening extending through 40 body 2 is divided into two circular working chambers 12—12' by inserting a separate wall or partition 14 therein, and this partition or division wall 14 is in part of ring shape, to permit shaft 7 to pass therethrough, and includes a straight extension 15 adapted to sub-

divide a straight slot or passage 16 which extends radially outward in the body from the working chambers 12—12'. Thus two separate rectangular shapes are provided above the two working chambers 12—12', in which two abutment members or slides 17—17' may reciprocate in riding contact with the peripheral surfaces of two round pistons 18—18' on shaft 7. These pistons are eccentrically related to the axis of the circular working chambers 12—12', and a sealing contact is effected by a small sector 13 of each piston where curved on the same radius as the circular wall of the working chamber within which it rotates. The two pistons are also disposed one-hundred-and-eighty degrees apart on the shaft to counterbalance each other and effect a substantially continuous pumping action or flow of liquid through the pump.

The liquid to be pumped is drawn into body 2 at one side of the slides or abutments 17—17' and transferred by the rotating pistons through the working chambers to the opposite sides of the slides or abutments where it is discharged. The present pump is particularly distinguished in that the inlet 19 and outlet 20 for the pump are axially aligned on opposite sides of the body, and in that their inner reduced ends intersect and communicate with rounded channels 21—21 formed in and extending transversely of the flat side walls of vertical cross passage 16 in body 2. These channels 21—21 may be produced in one operation by reaming or drilling a round opening in the body from face to face on a straight line or axis extending centrally through the straight passage or slot 16. The inlet and outlet openings, especially their reduced inner ends 22, may also be bored or reamed in one operation at right angles across slot 16 by having the inlet and outlet openings directly opposite each other or axially aligned. The partition extension 15 and the slides 17—17' prevent the liquid from passing directly from the inlet to the outlet, but each cross channel 21 permits the liquid to flow laterally across the faces of the slides from cover plate 4 to cover plate 4', and thence to the

circular working chambers 12—12' by way of grooves 23—23 milled vertically or lengthwise in the opposite faces of each slide or abutment member. However, the upper end 5 of each slide is not milled or grooved, so that the liquid is barred or checked from flowing upwardly into the upper end of cross passage 16, wherein an equalizing lever 24 is pivotally confined in rest position upon the flat 10 top edges of the slides or abutment members. This lever is notched or grooved centrally at its top to provide a seat for a pivot pin 25 carried by a short plunger 26 which is constantly pressed downwardly by a spring 15 27 held in place by a screw nut 28.

Accordingly, the vertical grooves in the slides or abutment members are the only open passages through which the liquid can flow freely into and out of the two working 20 chambers of the pump, and these grooves are entirely within the area of slot 16. Thus, the only gap or space in the circular wall of the working chambers to be bridged by the rotary pistons in their rotary travel, is 25 the relatively narrow slot or passage 16, which is only as wide as the slides or abutment members 17 are thick, and the sector portions of the pistons where they contact with the wall are of correspondingly small 30

area and need not be much larger or wider than the slot or passage 16 to be bridged, thereby permitting a working chamber of maximum size and capacity to be obtained in this type of pump. Manufacturing operations may also be expedited and costs reduced by constructing the pump body and abutment slides as herein described, and it has also been found advantageous to provide the extension 15 on partition ring 14 with 75 shouldered offsets or a slightly enlarged extremity 30 to permit this key-shaped partition member to be fitted readily within the key-shaped opening in the body. 80

What I claim is:

In a rotary pump as described, a main body having a circular opening extending therethrough and a slot extending outwardly from said opening, and a ring-shaped division wall adapted to fit within said circular opening, having a straight extension adapted to occupy said slot, the extremity of said straight extension being slightly enlarged and adapted to engage the side walls of said slot to promote a centering fit of the ring portion of said division wall within said circular opening. 90

In testimony whereof I affix my signature.

JOSEPH F. JAWOROWSKI.
